TRIM PANEL

Jesse Allen Bumpus and Herbert J. Woodall, Detroit, Mich., assignors to Woodall Industries Incorporated, Detroit, Mich., a corporation of Michigan

Application December 29, 1932, Serial No. 649,282

3 Claims. (Cl. 154—41)

Our invention relates to improvements in trim panels and to improvements in the method of manufacturing such panels.

It is particularly adaptable to interior trim panels for automobile bodies and is shown as embodied in such a panel and an improved process for manufacturing the same.

An object is to provide such a panel of three layers or laminations. The foundation layer is a fibrous composition panel board material and preferably one containing an asphaltum content which is inherently resistant to the attack of moisture. The outer layer is a layer of upholstery material such as woven cloth or artificial leather. The interior or intermediate layer is a layer of material which constitutes a barrier to the passage of moisture or of cleaning fluid solution as the same is commonly used and also serves the additional purpose of constituting an adhesive to secure the finishing material to the foundation board.

A meritorious feature of the invention is that the protecting intermediate layer is so applied that it is driven into the cut edges of the board so as to form within the porosities of the structure of the board a complete barrier layer to the passage of moisture thereinto. It also forms on the edges, because of its method of application, a reinforced barrier layer.

Other objects and meritorious characteristics of our improvement will further appear from the following specification, appended claims, and accompanying drawings, wherein

Fig. 1 is a diagrammatic layout of our improved process.

Fig. 2 is a diagrammatic layout of a modified form of our improved process.

Fig. 3 illustrates a step in the process.

Figs. 4 and 5 illustrates steps in the manufacture of the completed article.

Fig. 6 is a sectional view through the completed article.

The construction of our improved panel is explained from the preferred method of its manufacture which is illustrated in the drawings. We prefer to employ as a foundation board a composition fibrous material which contains a substantial quantity of a colloidal asphalt binder which renders the material inherently resistant to the attack of moisture. The treatment and process of manufacture provides that the outer plane surfaces of this material are substantially more resistant to the attack of moisture than the cut edges which result from the cutting of the material into the proper size and shape to

form panels. It is apparent, however, that other suitable foundation board material might be employed.

We intend to apply the covering material directly to the foundation board without the positioning of packing or wadding such as has hitherto been the common practice in this art. In the complete panel structure there will then be a foundation of composition fibrous material indicated as 10, an outer layer of covering material 12 and an intervening middle layer 14 or lamination of a suitable water and cleaning fluid resistant material which serves also the additional purpose of an adhesive to secure the covering material to the foundation board. This intermediate layer is of such a character that it extends in a reinforcement into the cut edges of the foundation layer. It is so applied that it is driven into the porosities of the cut edges of the foundation board so as to form a very complete barrier to prevent the passage of moisture at this critical point.

This intermediate layer also serves to prevent any of the ordinary cleaning fluids which are used to clean the outer covering material from penetrating into the foundation board and producing bleeding of the asphalt therefrom. It serves this purpose in addition to serving the purpose of preventing seepage of moisture into the board, particularly the cut edges, which would produce warping or buckling of the board and otherwise rendering it unsatisfactory for its purpose as a panel foundation.

In carrying out our improved process, different methods may be employed within limits, depending upon the materials used. In Figure 1 of the drawings we have shown diagrammatically a machine whereby a panel board 10 is passed through a pair of rollers 16 and 18. One of the rollers picks up from a vat 20 by roller 21 a suitable adhesive and protective coating compound which is applied to the one surface of the board as a coating 22. The coated surface of the board is then covered with a sheet of covering material 24 which has been cut to size and shape.

The board may then be passed along to another place in the line where the operator then applies under the force of suitable pressure mechanism such as indicated at 26 this adhesive protective compound to the cut edges of the board. This compound is applied under pressure so that it penetrates into the porosities of the edge structure. It also coats the adjacent portions of the covering material and the board on the rear face of the board. It thereby forms a reinforcement

of the coating at the edge of the board which overlies both surfaces of the board adjacent to the edge forcing itself in underneath the cloth at the edge of the board.

5 The covering material is then folded onto the back of the board as indicated at 28. This completes the covering of the board. It may then be delivered as desired. It will be seen that in the board resulting from this method of operation 10 the covering material is adhesively secured throughout its entire expanse to the board by a coating which not only serves as an adhesive but serves as a protective coating to the penetration of moisture either in the form of water or cleaning fluid solutions and that the cut edge portion 15 of the board has a reinforcement of this barrier therearound.

We have found that certain latex compounds 20 of a commercial character are highly satisfactory for this purpose and form an effective seal and barrier to the seepage of the moisture described and also form a peculiarly secure adhesion between the covering material and the foundation board.

25 Certain types of covering material are difficult to fasten down and in the case of artificial leather, which is a material of this character, I prefer to coat the surface of the covering material as well as the surface of the board. In this 30 case we may coat the artificial leather surface by spraying the latex adhesive compound thereon as at 25 in Fig. 4. This particular step in the process is illustrated in the modified showing of Fig. 2. The boards may here be put through 35 the machine but the covering material is spray coated as shown. These materials are then juxtaposed and additional coating is sprayed over the edge portions of the board being driven into the porosities thereof and the covering material 40 is then folded over on to the back of the board. It has been found that in carrying out this process that it is not necessary that the covering material after being sprayed with the coating be juxtaposed upon the coated surface of the 45 board within any very close time limit. This is of considerable importance in a production program. The coated covering material and the coated board may be brought together at such time as is convenient and the adhesion which 50 is obtained is a very secure one.

It is to be noted that in the present instance we have a complete panel structure which comprises three laminations. There is the foundation layer of the fibrous composition material 10 55 which contains the binder described. There is the outer layer 12 of covering material. There is the intermediate layer 14 which forms an adhesive binder and in addition forms a layer of protective material completely encasing that surface of the foundation board which is engaged by the covering material and particularly encasing cut edges of the board preventing ingress of moisture at this critical point.

The entire panel assembly may then be subjected to a stamping operation to provide suitable embossed designs thereon and for other purposes.

What we claim:

1. That method of fabricating a covered trim panel comprising cutting to size and shape a fibrous composition panel board, coating one surface of said board with an adhesive latex compound, providing a sheet of covering material 10 of the required size and shape to cover said surface of the board and to fold over the edges thereof on to the back of the board, and coating one surface of said sheet with an adhesive latex compound, applying said sheet of covering 15 material to the panel board bringing the coated surfaces of the two together, applying an adhesive latex compound under pressure to the cut edges of the board and folding the sheet of covering material over said cut edges and down upon 20 the back of the board to adhere thereto.

2. That method of fabricating a covered trim panel comprising cutting to size and shape a fibrous composition panel board, the plane surfaces of which are substantially impervious to 25 moisture and the cut edges of which are substantially more pervious to moisture, coating one surface of said board with an adhesive latex compound, providing a sheet of covering material 30 of the required size and shape to cover said surface of the board and to fold over the edges on to the back thereof and coating one surface of said sheet with an adhesive latex compound, applying said sheet to the board bringing the coated surfaces of the two together, applying an adhesive latex compound under pressure to the cut 35 edges of the board to be driven under pressure into the porosities of said cut edges forming a water proof barrier thereover, and applying the same adhesive compound to the adjacent portions of the board and the sheet of covering material, and folding the sheet of covering material over said cut edges and down upon the back 40 of the board to adhere thereto.

3. That method of fabricating a covered trim 45 panel comprising cutting to size and shape a fibrous composition panel board having cut edges which are relatively more pervious to moisture than the plain surfaces thereof, providing a layer of fabric covering material of required size 50 and shape to extend over one surface of the board and to fold over the edges unto the back thereof, securing said covering material to the surface of the board by a layer of moisture-proof adhesive compound, and applying moisture-proof 55 adhesive compound under pressure to the cut edges of the panel prior to the folding of said covering material over the edges of the panel so as to render the relatively pervious cut edges 60 resistant to moisture penetration.
